[57] CLAIM

The ornamental design for a data processing equipment cabinet, as shown and described.

DESCRIPTION

FIG. 1 is a top front and side perspective view of a data processing equipment cabinet showing our new design. FIG. 2 is a front elevational view thereof on an enlarged scale;

FIG. 3 is a rear elevational view thereof;

FIG. 4 is a top plan view thereof;

FIG. 5 is a side elevational view thereof;

FIG. 6 is a side elevational view thereof opposite that shown in FIG. 5; and,

FIG. 7 is a front elevational view of a second embodiment thereof the undisclosed views are identical in appearance to those of the first embodiment.

FIG. 1

FIG. 2
